UNITED STATES PATENT OFFICE.

ALEXANDER McNAMARA, OF RANDFONTEIN, TRANSVAAL.

SUPPORTING MEANS FOR BORING-RODS.

No. 827,814.

Specification of Letters Patent.

Patented Aug. 7, 1906.

Application filed December 29, 1903. Serial No. 187,049.

To all whom it may concern:

Be it known that I, ALEXANDER McNAMARA, a citizen of the United States, residing at Randfontein, Transvaal, have invented 5 certain new and useful Improvements in Supporting Means for Boring-Rods, of which the following is a specification.

This invention relates to boring apparatus and to a means for supporting and distributing the load or weight of the boring-rods. As at present constructed this is accomplished by means of a collar fixed onto the driving-spindle of the apparatus with ball-bearings arranged below and above said collar in such 15 manner that the lower bearing supports the load and permits the driving-spindle to be rotated, while the top bearing serves to take up any back thrust of the driving-spindle. From this it will be understood that the whole 20 weight of the boring-rods is carried by the lower bearing, and in boring to great depths this lower bearing is subjected to a large amount of wear. This results in the working of such apparatus being repeatedly stopped 25 for the removal and renewal of the balls or the grooved plates between which the balls are placed.

Now the object of the present invention is to obviate the defects of the existing arrangements and to construct the apparatus as to distribute the load or weight over a plurality of such bearings. The counterbalancing arrangement now used in deep boring is unnecessary with my invention.

35 The invention will now be described in detail by aid of the accompanying drawings.

In the drawings, Figure 1 shows the arrangement in front elevation. Fig. 2 is a sectional elevation. Fig. 3 is a sectional plan 40 on line $x'y$, Fig. 2; and Fig. 4 is a plan.

A represents the driving-spindle of the apparatus, which may be rotated in the ordinary or any other suitable manner. To the driving-spindle A are attached the boring-rods, and the connections between the same 45 may be made in the usual way. On the driving-spindle A is screwed or otherwise securely fixed the collar B, which serves for supporting the driving-spindle A and the boring-rods, attached thereto in such manner that 50 said spindle and rods may be freely rotated. Round the driving-spindle A above the fixed collar B is arranged a loose collar C, which is fitted with a bush c, of brass or other suitable metal. Between the collars B C is arranged

the thrust-bearing, which consists of the two rings or plates d d', which are grooved to receive the antifriction-balls d². This bearing is provided to take up any back thrust, and this arrangement embodies no feature of the 60 present invention. Round the driving-spindle A immediately below the fast collar B is arranged a loose sleeve or ferrule D. The ferrule D at the top abuts the under side of the fast collar B. Immediately beneath the collar B 65 and arranged round the upper portion of the ferrule D is an intermediate bearing of similar construction, to the top bearing or comprising the grooved plates e e', between which are interposed the antifriction-balls e². The 70 under side of the collar B rests on the top of the upper plate e, which latter is free to rotate round the sleeve D. Round the lower portion of the ferrule D is arranged a large plate E, which forms a central flange round the 75 driving-spindle A. In the top of the plate E is formed an annular recess in which is located the lower plate e' of the intermediate bearing. Round the driving-spindle A immediately beneath the center flange or plate 80 E is provided a third and bottom bearing of similar construction to the thrust and intermediate bearings. The top plate f of the bottom bearing fits into an annular recess formed in the under side of the plate E. The lower 85 extremity of the sleeve or ferrule D rests upon the top plate f of the bottom bearing. f' is the bottom plate of the bottom bearing, and f² represents the antifriction-balls interposed between the plates f f'. A ring or washer f³ 90 is arranged round the driving-spindle beneath the bottom plate f'. On the driving-spindle below the bottom bearing is loosely arranged the quill-flange F, and screwed into the flange or plate F is the brass or other quill G, which 95 loosely incloses the driving-spindle A.

In the edge of the intermediate plate or center flange E are screwed four stanchions or hangers in the form of downwardly-projecting eyepieces h. In the lower extremities of 100 the supports h are pivoted four horizontally-arranged levers h'. The levers h' project inward, and the tops of their inner ends project beneath and abut the bottom of the ring or washer f³. The levers h' are fulcrumed on 105 studs or centers i, arranged in the top of the quill-flange F.

The several parts of the arrangement are firmly connected by means of the four long tie-bolts j, which project through holes in the 110

loose collar C and quill-flange F and are secured by means of the nuts h , screwed on the extremities thereof.

The distribution of the load or weight between the intermediate and bottom bearings is effected by the fixed collar B, resting directly on the top bearing and transmitting approximately half of the load through the medium of the levers h' to the lower bearing.

10. In the arrangement illustrated the additional or bottom bearing receives approximately one-half of the weight or load.

It will be obvious that two or more additional bearings may be provided and that by

15 so arranging or fulcruming the levers h' the load may be more or less evenly distributed over the whole series of such bearings. In case two additional bearings are provided then the top set of levers h' would be ful-

20 crumed at a point approximately one-third of their length from the pivot and the lower set of levers be fulcrumed at a point about two-thirds of their length from the pivots, thus throwing approximately one-third of

25 the total load on each of the three bearings. In such an arrangement the top sleeve or ferrule D would be made thicker and the lower sleeve or ferrule for the lowermost bearing be arranged so as to rest against it at the bottom

30 end. Another plate, such as E, for carrying the lower set of levers would also be arranged between the plates E F and the centers i , for the upper set of levers would be fixed in the top of the additional plate.

35 Instead of providing four of the levers h' three or any other suitable number may be employed for each of the bearings.

What I claim as my invention, and desire to protect by Letters Patent, is—

40. 1. In apparatus of the nature specified, in combination, the driving-spindle and its supporting-collar fixed thereon, the ball-bearing extending round the driving-spindle upon which the collar rests, an additional ball-bearing extending round the driving-spindle beneath the bearing directly supporting the collar, and means for distributing the weight to be supported, between the two bearings, substantially as described.

45. 2. In apparatus of the nature specified, in combination, the driving-spindle and its supporting-collar fixed thereon, the ball-bearing extending round the driving-spindle upon which the collar rests, a plurality of additional ball-bearings extending round the driving-spindle beneath the bearing directly supporting the collar, and means for distributing the weight to be supported between the whole series of bearings, substantially as

50 described.

3. In apparatus of the class specified, in combination, the driving-spindle and its supporting-collar fixed thereon, the ball-bearing extending round the driving-spindle upon

55 which the collar rests, a center flange or plate

arranged below and supporting the bearing, an additional ball-bearing arranged below the plate and a sleeve or ferrule extending round the driving-spindle abutting at one extremity the supporting-collar and at the 70 other extremity resting on the additional bearing, and means carried by the center flange or plate for transmitting a portion of the weight of the boring-rods from the bearing immediately beneath the supporting-collar to the additional bearing arranged beneath said center flange or plate, substantially as described.

4. In apparatus of the class specified, in combination, the driving-spindle and the supporting-collar fixed thereon, the bearing surrounding the driving-spindle on which the supporting-collar rests, the center flange or plate extending round the driving-spindle for supporting the aforementioned bearing, an 85 additional bearing extending round the driving-spindle below the center plate, a sleeve or ferrule extending round the driving-spindle abutting at the one end the supporting-collar and at the other end resting upon the 90 additional bearing, and a series of levers carried by the center plate for distributing the weight between the two bearings, substantially as described.

5. In apparatus of the class specified in 95 combination, the driving-spindle A, the supporting-collar B fixed thereon, the center flange or plate E, the ball-bearing interposed between the supporting-collar B and plate or flange E, the ball-bearing beneath 100 the center flange or plate E, the ferrule or sleeve D surrounding the driving-spindle A abutting the supporting-collar B at the one end and resting at the other end on the bearing beneath the plate E, the hangers h fixed 105 in the center plate or flange E, the levers h' pivoted to the lower ends of the hangers h with their inner ends engaging the under side of the bearing below the plate or flange E, the quill-flange F and the centers i for the 110 levers h' arranged in the top of the quill-flange, substantially as described.

6. In apparatus of the class specified, in combination, the driving-spindle A, the supporting-collar B fixed thereon, the loose collar 115 C surrounding the driving-spindle, the thrust-bearing arranged between the top of the supporting-collar and the loose collar C, the ball-bearing extending round the driving-spindle upon which the supporting-collar rests the center flange or plate E, the ball-bearing extending round the driving-spindle below the center plate E, the sleeve or ferrule D extending round the driving-spindle, abutting at the one end the bottom of the supporting-collar and at the other end resting on the bearing beneath the plate E, the hangers h fixed in the flange or plate E, the levers h' pivoted to the hangers h at the one end and at their other and inner ends engaging the 125

130

under side of the bearing below the plate or flange E, the ring or washer f^3 between the bearing and the levers h' , the quill-flange F, the centers i fixed in the top of the quill-flange F in which the levers h' are fulcrumed and the quill G, substantially as described.

5 In witness whereof I have hereunto set my

hand in the presence of two subscribing witnesses.
